WILLIAM M. BLUME, OF NEW YORK, N. Y.

Letters Patent No. 73,869, dated January 28, 1868.

IMPROVEMENT IN MEASURING-RECEIVER FOR STILLS.

The Schedule referred to in these Letters Patent and making part of the same.

TO ALL WHOM IT MAY CONCERN:

Be it known that I, WILLIAM M. BLUME, of New York, in the county and State of New York, have invented a new and improved Receiver for Stills; and I do hereby declare that the following is a full, clear, and exact description thereof, which will enable those skilled in the art to make and use the same, reference being had to the accompanying drawings, forming part of this specification.

Figure 1 represents a side elevation, partly in section, of my improved receiver, the plane of section being indicated by the line xx' , fig. 2.

Figure 2 is a plan view, partly in section, of the same.

Figure 3 is a detail front view of the same.

Similar letters of reference indicate corresponding parts.

This invention relates to a new method of constructing the receiver of a whiskey or other still; and its object is to so arrange the same that the quantity of its contents, at the time of observation, can at once be ascertained, and also how high the liquid stood when it was highest in the receiver.

The invention consists, first, in the arrangement of a bar, having cups made of glass or other suitable material. This bar is set vertically within the receiver, and as the liquid rises within the same, the cups are filled to the same height to which the liquid rises, and if, by fraud or otherwise, some of the liquid should be removed, the cups will always show how high it stood. The bar, or a glass plate in the wall of the receiver, is also provided with a graduated scale, by means of which the contents of the still, at the time of observation, can at once be ascertained.

The invention consists, second, in arranging a series of perforated plates within the receiver, and around the aforesaid bar, whereby the liquid will be caused to rise steadily around the bar.

The invention also consists in the use of a perforated false cover to the receiver, whereby the removal of liquid from the receiver is prevented, except by pumping it out through a pipe in the said false cover. The real cover is closed down, and is locked by seal and Government stamp.

A, in the drawing, represents a receiver, to be attached to any suitable distilling-apparatus, or to any apparatus in which fluids are treated or prepared. The vessel A is made of sheet metal or other suitable material, and is provided with a hinged or other cover, A, which can be locked to the vessel by means of locks C C, or in any other suitable manner. By means of a vertical partition, D, the vessel A is divided into two compartments, a and b , the former the receiving, the latter the measuring-compartment. The compartment a is provided, near the top, with a fixed perforated cover, E, which prevents any liquor being removed from the vessel. Only through a hole, e , in the said cover E, may it be removed by pumping, if the cover B has been opened. The liquid enters the vessel through a pipe, F, which is fastened in the cover B, as shown. No liquid can thus be removed from the receiver by opening a cock in one of the pipes, as the pipe F is the only one connected with the receiver, and that enters the same at the top. To prevent the tapping of any of the pipes conducting the liquid from the still to any of the other vessels, I propose to cover the pipes with leather, cloth, or any other suitable material. The plate D is perforated at the bottom, and the liquid rises in the compartment b to the same height at which it stands in a . For the purpose of making the liquid rise steadily in the compartment b , a series of perforated partitions, G G' G'' and G''' , may be arranged in b , close to D, as shown. G is a wholly-perforated plate. G' has only holes at or near the bottom. G'' is wholly perforated, and G''' is again perforated at the lower end. The number of these plates may be varied at will. Within the compartment b is arranged a removable vertical bar, H, on which a series of small glass or other cups, I, is arranged. These cups receive the liquid in any suitable manner, either through their upper opening, or through extension-pipes, e . A portion of the outer wall of the partition b is made of glass or other transparent substance, as shown at d in figs. 1 and 2, so that the height of the liquid in the still may be observed from the outside. On a graduated scale, f , its height at the time of observation is recorded; while the cups I show how high it stood when it was highest. When the cover B is opened, the bar H can be taken out, and the contents of the cups can be fully inspected and recorded. Fraud against the revenue officers will be effectually prevented by the use of this apparatus.

Having thus described my invention, I claim as new, and desire to secure by Letters Patent—

1. The rod H, provided with the cups I I, whereby the height of the liquid is automatically recorded, as set forth.
2. The arrangement of the perforated plates D G and G¹, whereby the liquor is caused to enter the measuring-compartment b steadily, as described.
3. The perforated false cover E, when arranged below the real cover of a receiver, substantially as and for the purpose herein shown and described.
4. The arrangement and combination with each other, of the vessel A, plates D G G¹, covers B and E, rod H, and cups I, all made and operating substantially as and for the purpose herein shown and described.

WILLIAM M. BLUME.
